Elemir J. Ney, of Lowell, Mass.
Assignor to
The Lowell Manufacturing Company,
Letters Patent No. 1634, dated Aug. 12, 1862.

The schedule referred to in these Letters Patent and making part of the same.

To all whom it may concern:

Be it known that J. Elemir J. Ney, of Lowell, in the County of Middlesex and State of Massachusetts, have invented or produced an improvement on a design for carpets or other fabrics, of which the following is a full, clear and exact description, reference being had to the accompanying drawings, making part of this specification.

Drawing, No. 1, is the improved design.

Drawing, No. 2, is a design of French paper hanging. In corner A. of No. 1. is one fourth of a figure composed of four shells, surrounded by coral work, 1.

Corner B. is one fourth of a small eight pointed figure resting on a large figure 2. which has an irregular edge. Fig. 2. rests on the ground work of scales C. In corner 3. is one fourth of a large set figure resting on a diamond ground work. Fig. 4. is a bar composed of small regular work. The remaining parts are copied from the corresponding parts of drawing No. 2.

The colors employed for the different portions of the design may be varied to suit the taste and wish of the manufacturer.

Claim.

What I claim as my invention and desire to secure by Letters Patent, is the improvement in the design or pattern for carpets or other fabrics herein set forth. I disclaim all parts of drawing No. 1, which are copied from drawing No. 2, and not set forth in the specification.
